UNITED STATES PATENT OFFICE.

ROBERT BRANHAM, OF BELTON, TEXAS.

PUMP.

SPECIFICATION forming part of Letters Patent No. 461,417, dated October 20, 1891.

Application filed February 14, 1891. Serial No. 381,488. (No model.)

To all whom it may concern:

Be it known that I, ROBERT BRANHAM, a citizen of the United States, residing at Belton, in the county of Bell and State of Texas, 5 have invented a new and useful Pump, of which the following is a specification.

This invention relates to pumps; and it has for its object to provide a pump which shall be especially adapted for deep wells, and 10 which shall be simple in construction, durable, and efficient in operation.

With these ends in view the invention consists in the improved construction, arrangement, and combination of parts, which will 15 be hereinafter fully described, and particularly pointed out in the claim.

In the drawings hereto annexed, Figure 1 is a vertical sectional view taken through the working barrel and strainer of my improved 20 pump. Fig. 2 is a perspective detail view, showing the parts constituting the plunger separated or detached from each other. Fig. 3 is a detail view of the strainer and foot-valve detached.

25 Like numerals of reference indicate like parts in all the figures.

1 designates the working barrel, which constitutes, as usual, a portion of the well-casing, but which is preferably made of brass or other 30 metal which is sufficiently durable and capable of receiving a smooth finish.

2 designates the strainer, which is likewise made of brass, perforated, as shown, and sufficiently heavy to support the superimposed 35 parts. The upper end of the strainer is screw-threaded interiorly for the reception of a disk or valve-seat 3, having an opening 4, and provided on its upper side with a bail 5.

6 designates an upwardly-opening valve, 40 which is mounted upon the valve-seat 3, and which has a screw-threaded recess 7 for the reception of the stem 8, which extends upwardly through a perforation 9 in the bail 5. The lower end of the working barrel is screw-threaded interiorly, as shown at 10, for the 45 reception of the upper half of the valve-disk 3, by means of which the strainer is thus connected with the lower end of the working barrel.

50 11 designates the plunger, which is composed of a tubular cylinder 12, screw-threaded

exteriorly at its upper end, and having at its lower end an annular flange 13.

14 designates the plunger-head, which has a central perforation 15, and is provided on 55 its under side with a screw-threaded recess 16 to engage the upper screw-threaded end of the cylinder 12. The latter is provided with a series of packing-rings 17, of which in the drawings hereto annexed three have been 60 shown, although it will be understood that a greater or less number may be used. These packing-rings are preferably made of brass, it being the intention in the construction of this pump to avoid as nearly as possible the 65 use of leather or similar perishable material.

18 designates the plunger-rod, which is provided at its lower end with diverging arms 19, terminating in screw-threaded portions or bolts 20, adapted to engage the perforations 70 21 in the plunger-head 14, to which the said diverging arms may be secured by means of nuts 22 on the under side. The arms 19 constitute a cage, in which is mounted a ball-valve 23, opening upwardly, as will be readily 75 understood.

The operation and advantages of my improved pump will be readily understood from the foregoing description, taken in connection with the drawings hereto annexed. On 80 the upstroke of the plunger the valve 23 drops to its seat and the superimposed water is lifted, while at the same time suction is created in the lower part of the working valve, causing the fluid to pass upwardly under the 85 foot-valve. On the downstroke the foot-valve is closed and the valve 23 is raised from its seat, permitting the fluid to pass through the plunger from the lower part of the working valve. 90

I am aware that pumps embodying the general principles herein shown and having a similar arrangement of valves are old and well known. Such I do not claim. I am not aware, however, that the detailed construction and arrangement of parts herein shown and described have been known or used prior to my invention. 95

Having thus described my invention, what I claim is— 100

In a pump, the combination of the working barrel screw-threaded interiorly at its lower

end, the strainer screw-threaded at its upper end and registering with the bore of the barrel and abutting against the lower end thereof, the exteriorly-threaded disk or valve-seat 5 engaging the threads of the barrel and strainer and joining the same together, said disk being provided with the central conical valve-seat and the upwardly-extending perforated bail, and the frusto-conical valve mounted on 10 said disk and having a detachable stem ex-

tending through and guided in said perforated bail, substantially as specified.

In testimony that I claim the foregoing as my own I have hereto affixed my signature in presence of two witnesses.

ROBT. BRANHAM.
